INVENTOR.

BY *Anson R. Bonham*
Coraeline D. Thret
his ATTORNEY.

UNITED STATES PATENT OFFICE.

ANSON R. BONHAM, OF PHILADELPHIA, PENNSYLVANIA.

DISPLAY-BOX.

1,296,158.

Specification of Letters Patent.

Patented Mar. 4, 1919.

Application filed January 10, 1918. Serial No. 211,140.

To all whom it may concern:

Be it known that I, ANSON R. BONHAM, a citizen of the United States, residing in Philadelphia, county of Philadelphia and

5 State of Pennsylvania, have invented new and useful Improvements in Display-Boxes, of which the following is a specification.

My invention relates to the structure of a combined packing or shipping and display 10 box, carton or the like for writing instruments, such as pencils, penholders, or the like, and referred to in the appended claims as pencils.

For an illustration of some of the various 15 forms my invention may take, reference may be had to the accompanying drawing, in which:

Figure 1 is a perspective view of a closed box or carton embodying my invention.

20 Fig. 2 is a vertical sectional view through the box or carton with the articles packed therein and before rupture of the overlaid cover sheet.

Fig. 3 is a sectional view, similar to Fig. 25 2, showing some of the articles in display position.

Fig. 4 is a vertical sectional view of a modified construction wherein the coöperating article support is differently placed.

30 Referring to Figs. 1, 2 and 3, the box portion B, of any suitable material, such as pasteboard or cardboard, has the bottom b upon which rests the downwardly turned ends a of the false bottom member c spaced 35 from the bottom b.

Upon the false bottom c and within the box B may be packed or suitably disposed the pencils, penholders or other desired articles P. The closure member C, of card- 40 board, pasteboard, or any other suitable material, fits the box B and comprises the cover sheet d having a plurality of perforations e disposed preferably in vertical register with similar perforations f in the false bottom c.

45 Pasted or otherwise secured upon the cover sheet d is the overlaid sheet g of paper or other suitable easily ruptured material which covers and preferably completely conceals the perforations e in the cover sheet d.

When the box is opened, the pencils or other articles P are removed and the closure C replaced to position, as indicated in Fig. 3. Then any suitable number of articles P are forced through the overlaid sheet g at the perforations e in the cover sheet d, passing

through the perforations e and then through the perforations f in the false bottom c, thereby displaying the articles P above the box, as indicated in Fig. 3.

60

In Fig. 4, in lieu of arranging the auxiliary supporting member as a false bottom c as in Figs. 2 and 3, the auxiliary supporting member c has parts upwardly turned, as indicated at h, and outwardly turned, as indicated at i, and thereby attached to the inside of the cover sheet d or merely held between the cover sheet d and the upper edges of the box B. In this case again the member c has the perforations f disposed beneath the perforations e in the cover sheet d, which is again overlaid by the sheet g, as described in connection with Figs. 1 to 3 inclusive.

65

70 In the case of Fig. 4, the pencils or articles 75 may be packed within the box B beneath the member c; and as in the case of Fig. 3, the pencils or articles upon removal from the box and replacement of the cover may be forced through the overlaid sheet g through the perforations e in the member d and thence through the perforations f in the member c, thereby holding the articles in display position, as indicated.

75

What I claim is:

1. A shipping and display box for pencils having a wall having incomplete perforations, and an auxiliary supporting member within the box forming a wall of a compartment for storing the pencils and having 90 perforations in register with the aforesaid incomplete perforations, whereby pencils removed from the storage compartment may be forced through said incomplete perforations to complete them and extended through 95 the perforations in said auxiliary supporting member to support said pencils in display position.

85

2. A shipping and display box for pencils having a wall having perforations, a 100 sheet on said wall overlying said perforations, and an auxiliary supporting member within the box forming a wall of a pencil storing compartment and having perforations in register with the aforesaid perforations, whereby pencils removed from the storage compartment may be forced through said overlaid sheet and said first named perforations and extended through the perforations in said auxiliary supporting member 105 to support said pencils in display position.

110

3. A storage and display box for pencils comprising a box member, a cover therefor, said cover having perforations, a sheet attached to said cover and covering said perforations, and an auxiliary supporting member having perforations and supported within said box and so disposed therein as to leave a storage space for pencils, whereby pencils removed from said storage space 5 may be forced through said sheet and the perforations covered thereby and extended through perforations in said auxiliary supporting member and held in display position outside of said cover by said cover and 10 said auxiliary member.
4. A storage and display box for pencils having a box body, a cover therefor having 15

incomplete perforations, an auxiliary supporting member having perforations, and means for supporting said auxiliary supporting member within said box spaced from the box cover and from the bottom of the box, the space on one side of said auxiliary member forming a storage compartment for pencils, whereby pencils removed from said storage compartment may be forced through said first named perforations to complete the same and to extend through perforations in said auxiliary supporting member to be held thereby in display position. 25

In testimony whereof I have hereunto affixed my signature this 9th day of January, 1918.

ANSON R. BONHAM
